(57) **CLAIM**

The ornamental design for an access door of a printer, as shown and described.

DESCRIPTION

FIG. 1 is a front, left, top, perspective view of an access door of a printer showing our new design;

FIG. 2 is a front, right, top, perspective view of the access door of a printer shown in FIG. 1;

FIG. 3 is a front, left, bottom, perspective view of the access door of a printer shown in FIG. 1;

FIG. 4 is a front, right, bottom, perspective view of the access door of a printer shown in FIG. 1;

FIG. 5 is a front elevational view of the access door of a printer shown in FIG. 1;

FIG. 6 is a left-side elevational view of the access door of a printer shown in FIG. 1;

FIG. 7 is a right-side elevational view of the access door of a printer or shown in FIG. 1;

FIG. 8 is a top plan view of the access door of a printer shown in FIG. 1; and,

FIG. 9 is a bottom plan view of the access door of a printer shown in FIG. 1.

The broken lines shown in the drawings represent portions of the access door of a printer that form no part of the claimed design.
